ELECTRIC HEATING APPARATUS

Ernest N. Calhoun, Pittsburgh, Pa., assignor to
Edwin L. Wiegand, Pittsburgh, Pa.Application August 18, 1938, Serial No. 225,523
In Canada May 1, 1937

24 Claims. (Cl. 219—20)

My invention relates to electric heating apparatus. One use to which my invention may be put is in connection with electric cooking ranges, or the like. The principal object of my invention is to provide new and improved apparatus of these types. This application is a continuation in part of my application Serial Number 79,515, filed May 13, 1936.

In the drawings accompanying this specification, and forming a part of this application, I have shown, for purposes of illustration, several forms which my invention may assume. In these drawings:

Figure 1 is a diagrammatic view of electric heating apparatus embodying my invention, and

Figures 2, 3, 4, 5, and 6 are diagrammatic views of other embodiments of my invention.

In Figure 1 there is shown, diagrammatically, an electrical heating device 10 connectable to a source of current through control switch means 11. The heating device 10 is here shown as comprising a plurality of unitary heating elements, in this instance two, 12, 13. The unitary heating elements 12, 13 are here shown as each of annular form, one of which, 12, is of larger diameter than the other, 13, and is adapted to be disposed around and concentric with the smaller annular element. The heating elements 12, 13 are here shown as comprising resistors 14, 15 which may be embedded in compacted granular refractory insulation in annular metallic sheaths 16, 17, these sheaths being diagrammatically indicated by dot and dash lines.

The control switch means 11 is here shown as including a pair of movable switch elements 18, 19 pivotally mounted and electrically connected to pivots 20, 21. The movable switch elements 18, 19 are here shown as adapted to assume four positions, which may be identified as *a*, *b*, *c*, and *d*, in accordance with the suffixes of the reference numerals of the relatively stationary contacts to be described. The first position is an "open" position, indicated by the insulating spots 22a, 23a.

In the second position, *b*, the movable switch element 19 is adapted to make contact with a contact 24b connected with a line conductor 41, which in this instance is the neutral conductor of a three wire source of current having outside conductors 42, 43. The three wire source desirably provides an electromotive force between an outside conductor and the neutral conductor of half that between the outside conductors. Also, in the second position, *b*, the switch element 19 is on an insulating spot 25b.

In the third position, *c*, the switch element 18 is on an insulating spot 26c, while the switch element 19 is adapted to make contact with a contact 27c. The contact 27c is here shown as connected to the line conductor 43, through a jumper 30 connecting the contact 27c with another contact 29d, the latter being connected through a conductor 31, to the line conductor 43.

In the fourth position, *d*, the switch element 18 is adapted to engage a contact 28d, which is connected, through a conductor 38, to the line conductor 43, while the switch element 19 is adapted to engage the contact 29d.

The outer line conductor, 42, is here shown as connected to a terminal 31 of the resistor 14, and this terminal, 31, is in turn connected, through a conductor 32, to a terminal 33 of the resistor 15.

The other terminal, 34, of the resistor 14 is connected, by a conductor 35, to the pivot 21 of the switch element 19, whereas the other terminal, 36, of the resistor 15 is connected, through a conductor 39, to the pivot 20 of the switch element 18.

The switch elements 18, 19 are here shown as operable in unison by an insulating cross bar 40.

The operation of the embodiment of the invention shown in Figure 1 is as follows. When the control switch means 11 is moved to its first operative position, *b*, the resistor 15 is connected directly across the neutral conductor 41 and the outside conductor 42, while the resistor 14 is not supplied with current at all. In the operative position *c* of the control switch means 11, the resistor 14 is connected across the two outside line conductors 42, 43, whereas the resistor 15 is not supplied with current. In the third operative position, *d*, the resistors 14, 15 are in parallel across the outside line conductors 42, 43.

The resistors 14, 15 are desirably so designed that each one of them will operate at its full heating capacity when the greatest available electromotive force is impressed thereon, so that if, by way of example, each of the resistors 14, 15 is designed to operate at its full heating capacity at 230 volts, both resistors will consequently operate at full heating capacity when the control switch means 11 is in position *d*, assuming that the electromotive force between the two outside conductors 42, 43 of the three wire system is 230 volts. By way of further example, if each of the resistors 14, 15 is designed to dissipate 1000 watts at 230 volts, then of course the heating device 10 will emit heat the rate of 2000 watts when the control switch means 11 is in position *d*. If 55

the heating device 10 is utilized in a cooking range this high heat may be utilized as and when desired and the distribution of heat will be such that a high heat is applied to a maximum area 5 of the object to be heated. On the other hand, when the control switch means is in position c, the heating device 10 will emit heat at the rate of 1000 watts, and, in the instance shown, the distribution of heat emission is of course 10 changed, and is localized in the annulus defined by the outer heating element 12. This latter rate and distribution of heat is particularly adapted for heating frying pans and griddles. When the control switch means 11 is in position 15 b only the central heating element 13 is in operation, and inasmuch as it has been assumed that the heating element 13 is designed to operate at full capacity at 230 volts, it will operate at a quarter of its capacity when 115 volts is im- 20 pressed thereon, as will be the case when the control switch means is in position b. Consequently, the heating device 10 will emit heat at the rate of only 250 watts and this heat is localized in the annulus which is defined by the 25 central heating element 13. The heating device is then particularly adapted for heating ob- jects where a low rate of heat transfer is desired, as, for example, in simmering.

While the apparatus illustrated in Figure 1 has 30 been described in connection with annular heating elements, it will be understood that while particular advantages flow from the use of such elements, other forms of elements may be utilized. Furthermore, as will be apparent to those skilled 35 in the art, if it is found desirable in connection with the uses to which the heating apparatus is to be put, that the order in which the heating elements are connected to the source of current may be changed so that, for example, the outer 40 heating element 12 may be connected across an outside conductor, as at 42, and the neutral conductor 41, to secure a low rate of heat emission, and the inner heating element 13 may be next connected across the outside line conductors 42, 45 43, to secure heat emission at the full capacity of that element, and then both heating elements 12, 13 may be connected across the outer line conductors 42, 43 to secure heat emission from both heating 50 elements at full capacity. In view of the foregoing, other arrangements will readily suggest themselves to those skilled in the art.

Figure 2 shows another embodiment of my invention in which two resistors 44, 45 are connectable to a three wire source of current, represented by conductors 46, 47, 48, through control switch means 49, in various ways. The resistor 44 has one terminal connected, through a conductor 50, to the line conductor 47 and the other terminal connected to the pivot of a movable 55 switch element 51. The other resistor 45 has one terminal connected, through a conductor 52, to the line conductor 48 and the other terminal connected to the pivot of a movable switch element 53, here shown as movable in unison with the switch element 51 through an insulated connecting bar 54. In the position of the control switch means 49 shown in Figure 2, the switch elements 51, 53 are in engagement with insulating 60 spots 55a, 56a and the resistors 44, 45 are there- 65 fore not supplied with current.

In the next position, b, the switch element 51 is adapted to engage a contact 57b which is here shown connected by means of a jumper 69 to a contact 61d, the jumper 69 being in turn connected, by a conductor 70, to the neutral conduc- 70

tor 46 of the three wire supply. In this position (b), the switch element 53 engages an insulating spot 58b.

In the next position, c, the switch element 51 engages an insulating spot 59c, whereas the switch element 53 engages a contact 60c, which is here shown as connected by a jumper 71 to a contact 62d, which is in turn connected, by a conductor 72, to the neutral conductor 46.

In the next position, d, the switch element 51 10 engages the contact 61d, and the switch element 53 engages the contact 62d.

In the next position, e, the switch element 51 15 engages a contact 63e, here shown as connected, by a conductor 73, to the outside line conductor 48, while in this position of the switch means the switch element 53 engages an insulating spot 64e.

In the next position, f, the switch element 51 20 engages an insulating spot 65f, whereas the switch element 53 engages a contact 66f, which is here shown as connected, by a conductor 74, to the outside line conductor 47.

In the next position, g, the switch element 51 25 engages a contact 67g, which is connected by means of a jumper 75 to the contact 63e and therefore to the line conductor 48, whereas in this same position the switch element 53 engages a contact 68g, here shown as connected by a jumper 76 to the contact 66f and therefore to the line conductor 47. 30

The operation of the apparatus shown in Figure 2 may be best described by assuming particular values of watts dissipated by the resistors 44, 45 and voltages supplied by the line conductors 46, 47, 48. Assuming that the resistor 45 is de- 35 signed to dissipate 1200 watts when an electromotive force of 230 volts is impressed thereon and that the resistor 44 is designed to dissipate 800 watts when an electromotive force of 230 volts is impressed thereon, and further, that the electromotive force between the neutral conductor 46 and either one of the outside conductors is 115 volts, then when the control switch means 49 is in position b, the resistor 44 is connected across the line conductor 47 and the neutral conductor 46, and therefore, since it is being operated at one-half its rated voltage, it will dissipate 200 watts. The other resistor, 45, is not being sup- 40 plied with current. In the next position, c, the resistor 44 is not being supplied with current but the resistor 45 is connected across the line conductor 48 and the neutral conductor 46 and is therefore being supplied with one-half rated voltage and consequently dissipates 300 watts. 45

In the next position, d, the resistor 44 is again connected across the line conductor 47 and the neutral conductor 46, and the resistor 45 is connected across the line conductor 48 and the neutral conductor 46. The resistor 44 therefore dis- 50 ssipates 200 watts whereas the resistor 45 dissipates 300 watts, so that the total dissipation from the two resistors together is 500 watts. In the next position, e, the resistor 44 is connected across the outside line conductors 47, 48 and therefore 55 has 230 volts impressed thereon and operates at its full rate of capacity of 800 watts; the resistor 45 is not supplied with current. In the next position, f, the resistor 44 is not supplied with current, but the resistor 45 is connected across the outside line conductors 47, 48 and therefore 60 operates at its full rate of capacity of 1200 watts. In the next position, g, both resistors 44, 45 are connected across the outside line conductors 47, 48, in parallel, and therefore each operates at 65 70

75

its full rated capacity, so that the total dissipation of the two resistors together is 2000 watts.

It will of course be apparent that the two resistors 44, 45 may be utilized to heat the same object, and furthermore, if desired, they may be embodied in annular heating elements just as are the resistors 14, 15 in the embodiment of Figure 1. If the resistor 45 is selected as that one embodied in the outer annular heating element and the resistor 44 is selected as that one embodied in the inner annular heating element, it will be apparent that in the first heating position, *b*, the inner resistor 44 will supply a low heat; in position *c* the outer resistor 45 will supply a higher heat; in position *d* both resistors 44, 45, acting together, will supply a still higher heat; in position *e* the inner resistor 44 will supply a still higher heat; in position *f* the outer resistor 45 will supply a still higher heat, whereas in position *g*, 20 the two resistors 44, 45 together will supply a maximum heat.

In the embodiment shown in Figure 3 a resistor 77 has one terminal connected, by a conductor 78, to an outside line conductor 101 of a three wire supply and its other terminal connected to the pivot of a switch element 80. Another resistor, 81, has one terminal connected to the pivot of another switch element, 82, and its other terminal connected to the pivot of still another switch element 83. The switch elements 80, 82, 83, as here shown, are operable in unison by means of an insulated connecting bar 84. In the position shown in Figure 3 all of the switch elements, 80, 82, 83, are in engagement with insulating spots 85a, 86a, 87a, respectively, and neither of the resistors 77, 81 is therefore supplied with current.

In the first operative position, *b*, the switch element 80 is in engagement with a contact 88b. The contact 88b is here shown as connected by means of a jumper 97 to a contact 90b which in this position is engaged by the switch element 83. Also, in this position the switch element 82 engages a contact 89b which is connected, by a conductor 98, to a tap, which may be adjustable, on 45 an auto transformer 99. The terminals of the auto transformer 99 are here shown as connected to the line conductor 101 and to the neutral conductor 100 of the three wire supply.

In the next position, *c*, the switch element 80 is in engagement with a contact 91c, here shown as connected by means of a jumper 103 with a contact 94d, in turn connected, by a conductor 104, to the neutral conductor 100. In this same position the switch elements 82, 83 are in engagement with insulating spots 92c, 93c.

In the next position, *d*, the switch element 80 is in engagement with the contact 94d, whereas the switch element 82 is in engagement with a contact 95d connected, by conductor 105, to the neutral conductor 100, and the switch element 83 is in engagement with a contact 96d connected to the outside line conductor 102.

For purposes of illustration, in describing the operation of the embodiment of Figure 3, it will be assumed, for example, that each of the resistors 77, 81 will operate at its full capacity when an electromotive force of 115 volts is impressed on its terminals. Let it be further assumed that each resistor has a full capacity of 1000 watts at 115 volts. In the first operative position, *b*, the resistors 77, 81 are connected in series with each other and if an electromotive force of 115 volts were applied to the outside terminals of these resistors, the two resistors together would dissipate 75 a quarter of their rated capacity, that is, 500

watts. However, when the control switch means is in the position *b* the series connected resistors 77, 81 do not have the full 115 volts between the line conductor 101 and the neutral conductor 100 applied thereto, but only a fraction thereof, as 5 determined by the position of the tap on the auto transformer 99. By way of example, if it is desired that the two series connected resistors shall dissipate 200 watts, the tap will be so selected that approximately 70 volts will be applied to the series 10 connected resistors 77, 81. In the next position, *c*, of the control switch means the resistor 77 is connected across the line conductor 101 and the neutral conductor 100 and therefore operates at its full rated capacity of 1000 watts. In this position the resistor 81 is not supplied with current. In the next position, *d*, the resistor 77 is again connected across the line conductor 101 and the neutral conductor 100 and the resistor 81 is connected across the line conductor 102 and the neutral conductor 100. Both resistors 77, 81 consequently operate at their full rated capacity, and together dissipate 2000 watts.

In the embodiment shown in Figure 4 a resistor 106 has one terminal connected to an outside 25 line conductor 131 of a three wire source and has its other terminal connected to the pivot of a switch element 107. Another resistor 108 has one terminal connected to the other outside line conductor 132 of the three wire source and its other terminal connected to the pivot of a switch element 109. An auto transformer 110 is here shown as having one terminal connected to the neutral conductor 130, and, if desired, the supply of current through the auto transformer may be controlled by a switch comprising a switch element 111 having a contact 115b connected to the other terminal of the auto transformer 110, the switch element 111 being connected, by a conductor 124, to the line conductor 131. The switch elements 40 111, 107, 109 are here shown as operable in unison by means of an insulated connection bar 125. In the position shown in Figure 4 the switch elements 111, 107, 109 are in engagement with insulating spots 112a, 113a, 114a, respectively, and no current is supplied to the resistors 106, 108. In the first operative position, *b*, the switch element 111 engages the contact 115b, the switch element 107 engages a contact 116b, here shown as connected, by a conductor 126, to a tap on the auto 50 transformer 110, whereas the switch element 109 is in engagement with an insulating spot 117b. In the next position, *c*, the switch elements 111, 107 engage insulating spots 118c, 119c, respectively, whereas the switch element 109 engages a contact 120c, here shown as connected, by a conductor 127, to the neutral conductor 130. In the next position, *d*, the switch element 111 engages an insulating spot 121d, whereas the switch element 107 engages a contact 122d, here shown as 60 connected, by a conductor 128, to the neutral conductor 130; and in the same position of the control switch means the switch element 109 engages a contact 123d, here shown as connected by a jumper 129 with the contact 120c and therefore 65 connected to the neutral conductor 130.

In considering the operation of the embodiment of Figure 4, it may be assumed again that resistors 106, 108 are each so designed that when an electromotive force of 115 volts is impressed, 70 each resistor will operate at full rated capacity of 1000 watts. In the first operative position, *b*, the switch element 111 engages the contact 115b and connects the auto transformer 110 across the line conductor 131 and the neutral conductor 75

188, whereas the switch element 187 engages the contact 186b and consequently causes an electro-motive force to be applied to the resistor 108 depending upon the position of the tap to the auto 5 transformer 110. If it is desired that the resistor 108 shall dissipate, for example, approximately 200 watts, the tap of the auto transformer 110 is so positioned that approximately 50 volts will be supplied from the auto transformer 110 to 10 the resistor 108. In the next position, c, of the control switch means the auto transformer 110 is disconnected from the circuit and the resistor 108 is not supplied with current, whereas the resistor 108 is connected across the line conductor 15 132 and the neutral conductor 130, and therefore dissipates 1000 watts. In the next position, d, of the control switch means the resistor 108 is connected across the line conductor 131 and the neutral conductor 130, whereas the resistor 108 is 20 connected across the line conductor 132 and the neutral conductor 130. Consequently, both resistors 106, 108 operate at their full rated capacity and together dissipate 2000 watts.

What has been stated in connection with form 25 and location of the resistors 44, 45 of the embodiment of Figure 2 applies equally well with respect to the resistors 71, 81 of the embodiment of Figure 3 and the resistors 106, 108 of the embodiment of Figure 4.

30 It will be apparent that a switch similar to the switch 111 of the embodiment of Figure 4 may be added to control the auto transformer 99 of the embodiment of Figure 3.

In the embodiment shown in Figure 5 a resistor 35 133 has one terminal connected to an outside line conductor 134 of a three wire supply and its other terminal connected to the pivot of a switch element 140. Another resistor, 143, has one terminal connected to the pivot of another 40 switch element, 141, and its other terminal connected to the pivot of still another switch element 142. The switch elements 140, 141, 142, as here shown, are operable in unison by means of an insulated connecting bar 144. In the position shown in Figure 5 all of the switch elements, 45 140, 141, 142, are in engagement with insulating spots 137a, 138a, 139a, respectively, and neither of the resistors 133, 143 is therefore supplied with current.

50 In the first operative position, b, the switch element 140 is in engagement with a contact 137b. The contact 137b is here shown as connected by means of a jumper 145 to a contact 137c, the jumper 145 being connected by a conductor 146 to the other outside conductor, 136, of the three wire supply. In position b the switch element 141 engages a contact 138b which is connected by a conductor 147 to the line conductor 134; and the switch element 142 engages a contact 139b. The contact 139b is connected by a jumper 148 to a contact 139d which is connected to the conductor 146 and hence also to the line conductor 136.

In the next position, c, the switch element 140 65 engages the contact 137c; and the switch elements 141, 142 engage insulating spots 138c, 139c respectively.

In the next position, d, the switch element 140 70 engages an insulating spot 137d; the switch element 141 engages the contact 138d which is connected by a jumper 149 to the contact 138b and hence to the conductor 147; and the switch element 142 engages the contact 139d.

In the next position, e, the switch element 140 75 engages a contact 137e which is connected by a

conductor 150 to the neutral conductor, 135, of the three wire supply; and the switch elements 141, 142 engage insulating spots 138e, 139e respectively.

In the next position, f, the switch element 140 5 5 engages a contact 137f which is connected by a jumper 151 to a contact 138f which in this position is engaged by the switch element 141; and the switch element 142 engages a contact 139f which is connected by a conductor 152 to the neutral conductor 135.

The operation of the embodiment shown in Figure 5 is as follows. Let it be assumed, merely by way of example, that each of the resistors 133, 143 is designed to operate at full rated capacity 15 when individually connected across the outside conductors 134, 136 of the three wire supply, and that these conductors supply a voltage of 230 volts, and that when so connected each of the resistors dissipates 1000 watts. In that case 20 when the switch elements 140, 141, and 142 are in position b, each of the resistors 133, 143 will be connected across the conductors 134, 136 and the total dissipation will be 2000 watts. In position c the resistor 133 will be connected across 25 the conductors 134, 136, and the resistor 143 will not be supplied with current. Accordingly the total dissipation is 1000 watts. In position d the resistor 143 will be connected across the conductors 134, 136, and the resistor 133 will not be 30 supplied with current, and accordingly the total dissipation will again be 1000 watts. In this instance the resistors 133, 143 desirably define different areas, and may be, for example, of concentric annular form as described in connection 35 with Figure 1, and the resistor 133 may be the outer unit and the resistor 143 may be the inner unit. Accordingly, a dissipation of 1000 watts may be obtained either in a large annulus or in a small annulus, so that, if desired, the smaller 40 annulus may be used for more efficient heating of small utensils. In position e the resistor 133 is connected across the conductors 134, 135 and accordingly is supplied with 115 volts and therefore dissipates 250 watts. The resistor 143 is 45 not supplied with current in this position. In position f the resistors 133, 143 are connected in series across the conductors 134, 135, each then dissipating 62.5 watts, so that the total dissipation is 125 watts.

In the embodiment shown in Figure 6 a resistor 153 has one terminal connected to an outside line conductor 154 of a three wire supply and its other terminal connected to the pivot of a switch element 160. Another resistor, 163, 55 has one terminal connected to a pivot of another switch element 161, and its other terminal connected to the pivot of still another switch element 162. The switch elements 160, 161, 162, as here shown, are operable in unison by means of 60 an insulated connecting bar 164. In the position shown in Figure 6 all of the switch elements 160, 161, 162 are in engagement with insulating spots 157a, 158a, 159a, respectively, and neither of the resistors 153, 163 is therefore supplied with 65 current.

In the first operative position, b, the switch element 160 is in engagement with a contact 157b which is connected by a conductor 165 to the other outside line conductor, 156; the switch element 161 is in engagement with a contact 158b which is connected by a conductor 166 with the line conductor 154; and the switch element 162 engages a contact 159b which is connected by a jumper 167 to contacts 159c, 159d, the jumper 70

being connected by a conductor 168 to the line conductor 156.

In the next position, *c*, the switch element 160 engages an insulating spot 157c; the switch element 161 engages a contact 158c connected by a jumper 169 to the contact 158b and hence to the line conductor 154; and the switch element 162 engages the contact 159c connected by the jumper 167 and the conductor 168 to the conductor 156.

In the next position, *d*, the switch element 160 engages a contact 157d connected by a jumper 170 to a contact 157f in turn connected by a conductor 171 to a contact 158d, the latter being engaged by the switch element 161 in this position; and the switch element 162 engages the contact 159d.

In the next position, *e*, the switch element 160 engages an insulating spot 157e; the switch element 161 engages the contact 158e; and the switch element 162 engages a contact 159e connected by a conductor 172 to the neutral conductor, 155, of the three wire supply.

In the next position, *f*, the switch element 160 engages the contact 157f; the switch element engages a contact 158f which is connected by a jumper 173 to the contact 158d and hence to the conductor 171; and the switch element 162 engages a contact 159f connected by a jumper 174 to the contact 159e and hence to the conductor 172.

The operation of the embodiment shown in Figure 6 is as follows. Let it again be assumed that each of the resistors 153 and 163 will operate at full rated capacity and dissipate 1000 watts when individually supplied with 230 volts. In position *b* both of the resistors 153 and 163 are connected across the conductors 154, 156, assumed to supply 230 volts, and accordingly the total dissipation is 2000 watts. In position *c* the resistor 163 is connected across the conductors 154, 156, and the resistor 153 is not supplied with current. Accordingly the total dissipation is 1000 watts. In position *d* the resistors 153, 163 are connected in series across the conductors 154, 156, each then dissipating 250 watts so that the total dissipation is 500 watts. In position *e* the resistor 163 is connected across the conductors 154, 155, whereas the resistor 153 is not supplied with current. The resistor 163 being supplied with 115 volts, dissipates 250 watts. In position *f* the resistors 153, 163 are connected in series across the conductors 154 and 155, each then dissipating 62.5 watts so that the total dissipation is 125 watts. It will of course be evident that in this embodiment as well as in the other disclosed embodiments the resistors 153, 163 may be in concentric annular form as described in connection with Figure 1. For example, the resistor 153 may be the outer annulus and the resistor 163 may be the inner annulus.

It will be apparent that if desirable, the resistors in any one of the embodiments may be designed to operate at different full rated heating capacity.

In general, it should be understood that while the operation of the embodiments of the invention has been described in connection with particular suitable rated capacities of the resistors or heating elements and with respect to particular electromotive forces impressed thereon, that my invention is not limited to these particular values.

From the foregoing it will be apparent to those skilled in the art that each of the illustrated

embodiments of my invention provides a new and improved electric heating apparatus, and accordingly, each accomplishes the principal object of my invention. On the other hand, it also will be obvious to those skilled in the art that the illustrated embodiments of my invention may be variously changed and modified, or features thereof, singly or collectively, embodied in other combinations than those illustrated, without departing from the spirit of my invention, or sacrificing all of the advantages thereof, and that accordingly, the disclosure herein is illustrative only, and my invention is not limited thereto.

I claim:

1. In an electric heating apparatus connectable to a plurality of conductors different pairs of which provide different electromotive forces, the combination of: a plurality of resistors constructed to operate at full heating capacity when individually connected across that pair of said conductors providing the highest electromotive force; switch means having a plurality of movable elements and a common operating means for moving said elements in unison to different positions; and means, including electrical connections, so constructed and arranged that said switch means is adapted to interconnect one or more of said resistors and one or more of said pairs of conductors in different relationships for said different positions of said switch means respectively.

2. In an electric heating apparatus connectable to a plurality of conductors different pairs of which provide different electromotive forces, the combination of: a plurality of resistors constructed to operate at full heating capacity when individually connected across that pair of said conductors providing the highest electromotive force; switch means having a plurality of movable elements and a common operating means for moving said elements in unison to different positions; and means, including electrical connections, so constructed and arranged that said switch means is adapted to interconnect one or more of said resistors and one or more of said pairs of conductors in different relationships for said different positions of said switch means respectively, at least one of said resistors in at least one of said positions of said switch means being connected, through said switch means, across a pair of said conductors providing an electromotive force less than said highest electromotive force.

3. In an electric heating apparatus connectable to a plurality of conductors different pairs of which provide different electromotive forces, the combination of: a plurality of resistors constructed to operate at full capacity when electromotive force corresponding to that furnished by a predetermined pair of said conductors is individually applied thereto; switch means having a plurality of movable elements and a common operating means for moving said elements in unison to different positions; and means, including electrical connections, so constructed and arranged that in one position of said switch means at least two of said resistors are so connected to certain of said conductors that they operate at full heating capacity, and in a succeeding position of said switch means one only of said resistors is so connected to certain of said conductors that it operates at full heating capacity, and in a succeeding position of said switch means one only of said resistors is connected to certain of said conductors and is so connected that it operates at less than full heating capacity.

4. In an electric heating apparatus connect-

able to a plurality of conductors different pairs of which provide different electromotive forces, the combination of: a plurality of resistors constructed to operate at full capacity when individually connected across that pair of conductors providing the highest electromotive force; switch means having a plurality of movable elements and a common operating means for moving said elements in unison to different positions; and means, including electrical connections, so constructed and arranged that in one position of said switch means at least two of said resistors are connected across that pair of conductors providing the highest electromotive force, and in a succeeding position of said switch means at least one of said resistors is connected across a pair of said conductors providing an electromotive force less than said highest electromotive force.

5. In an electric heating apparatus connectable to a plurality of supply line conductors different pairs of which provide different electromotive forces, the combination of: a plurality of resistors constructed to operate at full capacity when electromotive force corresponding to that furnished by a predetermined pair of said supply line conductors is applied thereto; an autotransformer, having its end terminals connected to one of said pairs of supply line conductors, said pair furnishing an electromotive force substantially less than the electromotive force furnished by another pair of said supply line conductors, said autotransformer having a tap between said end terminals; switch means having a plurality of movable elements and a common operating means for moving said elements in unison to different positions; and means, including electrical connections, so constructed and arranged that said switch means is adapted to interconnect one or more of said resistors with one or more of said pairs of supply line conductors or with said tap and one of said supply line conductors in different relationships for said different positions of said switch means respectively.

6. In an electric heating apparatus connectable to a plurality of supply line conductors different pairs of which provide different electromotive forces, the combination of: a plurality of resistors constructed to operate at full capacity when electromotive force corresponding to that furnished by a predetermined pair of said supply line conductors is individually applied thereto; an autotransformer, having its end terminals connected to one of said pairs of supply line conductors, and having a tap between said end terminals; switch means having a plurality of movable elements and a common operating means for moving said elements in unison to different positions; and means, including electrical connections, so constructed and arranged that said switch means is adapted to interconnect one or more of said resistors with one or more of said pairs of supply line conductors or with said tap and one of said supply line conductors in different relationships for said different positions of said switch means respectively and in one of which relationships at least two of said resistors are connected in series across said tap and one of said line conductors.

7. In an electric heating apparatus connectable to a plurality of supply line conductors dif-

ferent pairs of which provide different electromotive forces, the combination of: a plurality of resistors constructed to operate at full capacity when electromotive force corresponding to that furnished by a predetermined pair of said supply line conductors is individually applied thereto; an autotransformer, having its end terminals connected to one of said pairs of supply line conductors, and having a tap between said end terminals; switch means having a plurality of movable elements and a common operating means for moving said elements in unison to different positions; and means, including electrical connections, so constructed and arranged that in one position of said switch means at least two of said resistors are so connected to said supply line conductors that they operate at full heating capacity, and in a succeeding position of said switch means one only of said resistors is so connected to said supply line conductors that it operates at full capacity, and in a succeeding position of said switch means one of said resistors is connected across one of said supply line conductors and said tap and operates at less than full heating capacity.

8. In an electric heating apparatus connectable to a plurality of conductors different pairs of which provide different electromotive forces, the combination of: a plurality of resistors constructed to operate at full heating capacity when individually connected across that pair of said conductors providing the highest electromotive force, one of said resistors being constructed to operate at a full heating capacity different from another of said resistors; switch means having a plurality of movable elements and a common operating means for moving said elements in unison to different positions; and means, including electrical connections, so constructed and arranged that said switch means is adapted to interconnect one or more of said resistors and one or more of said pairs of conductors in different relationships for said different positions of said switch means respectively.

9. In an electric heating apparatus connectable to a plurality of conductors different pairs of which provide different electromotive forces, the combination of: a plurality of resistors constructed to operate at full heating capacity when individually connected across that pair of said conductors providing the highest electromotive force, one of said resistors being constructed to operate at a full heating capacity different from another of said resistors; switch means having a plurality of movable elements and a common operating means for moving said elements in unison to different positions; and means, including electrical connections, so constructed and arranged that said switch means is adapted to interconnect one or more of said resistors of different capacities to conductors providing the highest electromotive force in different relationships for different positions of said switch means, and to interconnect one or more of said resistors of different capacities to conductors providing less than the highest electromotive force in different relationships for other different positions of said switch means.

10. In an electric heating apparatus connectable to a plurality of conductors different pairs of which provide different electromotive forces, the combination of: a plurality of resistors constructed to operate at full heating capacity when individually connected across a pair of conductors providing the highest electromotive force, one of

- said resistors being constructed to operate at a full heating capacity different from another of said resistors; switch means having a plurality of movable elements and a common operating means for moving said elements in unison to different positions; and means, including electrical connections, so constructed and arranged that said switch means is adapted to interconnect one or more of said resistors and one or more of said 5 pairs of conductors in different relationships for said different positions of said switch means respectively, a resistor of less capacity than another of said resistors, being connected through said switch means in at least one of said positions of 10 said switch means, across a pair of said conductors providing an electromotive force less than said highest electromotive force.
11. In an electric heating apparatus connectable to a plurality of supply conductors different 20 pairs of which provide different electromotive forces, the combination of: a plurality of resistors constructed to operate at full heating capacity when individually connected across that pair of said conductors providing the highest electromotive force; switch means having a plurality of movable elements and a common operating means for moving said elements in unison to a plurality of different positions; means, separate from said switch means, constructed and arranged to connect one terminal of each of said resistors to a supply conductor; and means, including additional electrical connections, so constructed and arranged that said switch means is adapted to interconnect one or more of said 25 resistors and one or more of said pairs of conductors in different relationships for said plurality of different positions of said switch means respectively.
12. In an electric heating apparatus connectable to a plurality of conductors different pairs of which provide different electromotive forces, the combination of: a plurality of resistors constructed to operate at full heating capacity when individually connected across that pair of said 30 conductors providing the highest electromotive force; switch means having a plurality of movable elements and a common operating means for moving said elements in unison to a plurality of different positions; said switch means including relatively stationary contact means with which one of said movable elements is cooperable in two different positions respectively of said element; means, separate from said switch means, constructed and arranged to connect one terminal of each of said resistors to a supply conductor; and means, including additional electrical connections, so constructed and arranged that said switch means is adapted to interconnect one or more of said 35 resistors and one or more of said pairs of conductors in different relationships for said plurality of different positions of said switch means respectively.
13. In an electric heating apparatus connectable to a plurality of conductors different pairs of which provide different electromotive forces, the combination of: a plurality of resistors constructed to operate at full heating capacity when individually connected across that pair of said 40 conductors providing the highest electromotive force; switch means having a plurality of movable elements and a common operating means for moving said elements in unison to a plurality of different positions; said switch means including relatively stationary contact means with which one of said movable elements is cooperable in two different positions respectively of said element; means, separate from said switch means, constructed and arranged to connect one terminal of each of said resistors to a supply conductor; and means, including additional electrical connections, so constructed and arranged that said switch means is adapted to interconnect one or more of said 45 resistors and one or more of said pairs of conductors in different relationships for said plurality of different positions of said switch means respectively.
14. In an electric heating apparatus connectable to a plurality of supply conductors different pairs of which provide different electromotive forces, the combination of: a plurality of resistors constructed to operate at full heating capacity when individually connected across that pair of said conductors providing the highest electromotive force; switch means having a plurality of movable elements and a common operating means for moving said elements in unison to a plurality of different positions; said switch means including relatively stationary contact means with which one of said movable elements is cooperable in two different positions respectively of said element; means, separate from said switch means, constructed and arranged to connect one terminal of each of said resistors to a supply conductor; and means, including additional electrical connections, so constructed and arranged that said switch means is adapted to interconnect one or more of said 50 resistors and one or more of said pairs of conductors in different relationships for said plurality of different positions of said switch means respectively.
15. In an electric heating apparatus connectable to a three wire supply system comprising main conductors and a neutral conductor, the combination of: two resistors constructed to operate at full heating capacity when individually connected across the main conductors; switch means having two movable elements and a common operating means for moving said elements in unison to a plurality of different positions; said switch means including relatively stationary first contact means with which one of said elements is cooperable in two different positions respectively of said element, and including also relatively stationary second contact means comprising at least one contact with which the other of said elements is cooperable in one of its positions, and including also relatively stationary third contact means comprising at least one contact with which said other of said elements is cooperable in another of its positions; means for connecting said first contact means and said at least one of said contacts of said second contact means to one of said main conductors; means for connecting said at least one of said contacts of said third contact means to said neutral conductor; means for connecting said terminal of each of said resistors to the other of said main conductors; and means for connecting the other terminals of said resistors to said 55 movable elements respectively.
16. In an electric heating apparatus connectable to a plurality of conductors different pairs of which provide different electromotive forces,

the combination of: a plurality of resistors constructed to operate at full heating capacity when individually connected across a predetermined pair of said conductors; switch means having a 5 plurality of movable elements and a common operating means for moving said elements in unison to a plurality of different positions; said switch means including relatively stationary contact means with which one of said movable elements 10 is cooperable in two different positions respectively of said element; means, separate from said switch means, constructed and arranged to connect said contact means to one of said conductors; means, separate from said switch means, 15 constructed and arranged to connect one terminal of each of said resistors to one of said conductors; and means, including additional electrical connections, so constructed and arranged that said switch means is adapted to interconnect one 20 or more of said resistors and one or more of said pairs of conductors in different relationships for said plurality of different positions of said switch means respectively.

17. In an electric heating apparatus connectable to a plurality of conductors different pairs of which provide different electromotive forces, the combination of: a plurality of resistors constructed to operate at full capacity when electromotive force corresponding to that furnished by 25 a predetermined pair of said conductors is individually applied thereto; switch means having a plurality of movable elements and a common operating means for moving said elements in unison to different positions; and means, including 30 electrical connections, so constructed and arranged that in one position of said switch means at least two of said resistors are so supplied by certain of said conductors that they operate at full heating capacity, and in a succeeding position of said switch means one only of said resistors is so supplied by certain 35 of said conductors that it operates at less than full heating capacity, and in a succeeding position of said switch means one only of said resistors is so supplied by certain of said conductors that it operates at 40 full heating capacity, and in a succeeding position of said switch means one only of said resistors is so supplied by certain of said conductors that each of said at 45 least two resistors operates at less than full heating capacity.

18. In an electric heating apparatus connectable to a plurality of conductors different pairs of which provide different electromotive forces, the combination of: a plurality of resistors constructed to operate at full capacity when electromotive force corresponding to that furnished by a predetermined pair of said conductors is individually applied thereto; switch means having a 50 plurality of movable elements and a common operating means for moving said elements in unison to different positions; and means, including electrical connections, so constructed and arranged that in one position of said switch means at least two of said resistors are so supplied by certain of said conductors that they operate at full heating capacity, and in a succeeding position of said switch means one only of said resistors is so supplied by certain of said conductors that it operates at 55 full heating capacity, and in a succeeding position of said switch means one only of said resistors is so supplied by certain of said conductors that it operates at full heating capacity, and in a succeeding position of said switch means at least one different one of said resistors is so supplied by certain of said conductors that it operates at 60 full heating capacity.

19. In an electric heating apparatus connectable to a plurality of conductors different pairs of which provide different electromotive forces, the combination of: a plurality of resistors constructed to operate at full capacity when electromotive force corresponding to that furnished by a 70 predetermined pair of said conductors is individually applied thereto; switch means having a 75

predetermined pair of said conductors is individually applied thereto; switch means having a plurality of movable elements and a common operating means for moving said elements in unison to different positions; and means, including electrical connections, so constructed and arranged that in one position of said switch means at least two of said resistors are so supplied by certain of said conductors that they operate at full heating capacity, and in a succeeding position of said switch means one only of said resistors is so supplied by certain of said conductors that it operates at full heating capacity, and in a succeeding position of said switch means at least two of said resistors are so supplied by certain of said conductors that each of said at least two resistors operates at less than full heating capacity.

20. In an electric heating apparatus connectable to a plurality of conductors different pairs of which provide different electromotive forces, the combination of: a plurality of resistors constructed to operate at full capacity when electromotive force corresponding to that furnished by a predetermined pair of said conductors is individually applied thereto; switch means having a plurality of movable elements and a common operating means for moving said elements in unison to different positions; and means, including electrical connections, so constructed and arranged that in one position of said switch means at least two of said resistors are so supplied by certain of said conductors that they operate at full heating capacity, and in a succeeding position of said switch means one only of said resistors is so supplied by certain of said conductors that it operates at 25 full heating capacity, and in a succeeding position of said switch means one only of said resistors is so supplied by certain of said conductors that it operates at less than full heating capacity, and in a succeeding position of said switch means at least two of said resistors are so supplied by certain of said conductors that each of said at 30 least two resistors operates at less than full heating capacity.

21. In an electric heating apparatus connectable to a plurality of conductors different pairs of which provide different electromotive forces, the combination of: a plurality of resistors constructed to operate at full capacity when electromotive force corresponding to that furnished by a predetermined pair of said conductors is individually applied thereto; switch means having a plurality of movable elements and a common operating means for moving said elements in unison to different positions; and means, including electrical connections, so constructed and arranged that in one position of said switch means at least two of said resistors are so supplied by certain of said conductors that they operate at full heating capacity, and in a succeeding position of said switch means at least one of said resistors is so supplied by certain of said conductors that it operates at full heating capacity, and in a succeeding position of said switch means at least one different one of said resistors is so supplied by certain of said conductors that it operates at 55 full heating capacity.

22. In an electric heating apparatus connectable to a plurality of conductors different pairs of which provide different electromotive forces, the combination of: a plurality of resistors constructed to operate at full capacity when electromotive force corresponding to that furnished by a predetermined pair of said conductors is individually applied thereto; switch means having a 70

plurality of movable elements and a common operating means for moving said elements in unison to different positions; and means, including electrical connections, so constructed and arranged that in one position of said switch means at least two of said resistors are so supplied by certain of said conductors that they operate at full heating capacity, and in a succeeding position of said switch means one only of said resistors 5 is so supplied by certain of said conductors that it operates at full heating capacity, and in a succeeding position of said switch means a different one only of said resistors is so supplied by certain of said conductors that it operates at full 10 heating capacity, and in a succeeding position of said switch means at least one of said resistors is so supplied by certain of said conductors that it operates at less than full heating capacity.

23. In an electric heating apparatus connectable to a plurality of conductors different pairs of which provide different electromotive forces, the combination of: a plurality of concentrically disposed annular resistors constructed to operate at full capacity when electromotive force corresponding to that furnished by a predetermined pair of said conductors is individually applied thereto; switch means having a plurality of movable elements and a common operating means for moving said elements in unison to different positions; and means, including electrical connections, so constructed and arranged that in one 20 position of said switch means at least two of said resistors are so supplied by certain of said conductors that they operate at full heating capacity, and in a succeeding position of said switch means one only of said resistors is so supplied by certain 25 of said conductors that it operates at full heating capacity, and in a succeeding position of said switch means a different one only of said resistors is so supplied by certain of said conductors that it operates at full heating capacity, and in a succeeding position of said switch means at least one of said resistors is so supplied by certain of said conductors that it operates at less than full heating capacity.

at least one of said resistors is so supplied by certain of said conductors that it operates at full heating capacity, and in a succeeding position of said switch means at least one different one of said resistors is so supplied by certain of said conductors that it operates at full heating capacity. 5

24. In an electric heating apparatus connectable to a plurality of conductors different pairs of which provide different electromotive forces, 10 the combination of: a plurality of concentrically disposed annular resistors constructed to operate at full capacity when electromotive force corresponding to that furnished by a predetermined pair of said conductors is individually applied 15 thereto; switch means having a plurality of movable elements and a common operating means for moving said elements in unison to different positions; and means, including electrical connections, so constructed and arranged that in one 20 position of said switch means at least two of said resistors are so supplied by certain of said conductors that they operate at full heating capacity, and in a succeeding position of said switch means one only of said resistors is so supplied by certain 25 of said conductors that it operates at full heating capacity, and in a succeeding position of said switch means a different one only of said resistors is so supplied by certain of said conductors that it operates at full heating capacity, and in a succeeding position of said switch means at least one of said resistors is so supplied by certain of said conductors that it operates at less than full heating capacity.

ERNEST N. CALHOUN. 35
